(57) **CLAIM**

The ornamental design for "access control machine," as shown and described.

DESCRIPTION

FIG. 1 is a front perspective view of an access control machine in accordance with a first embodiment showing my new design;

FIG. 2 is a rear perspective view in accordance with the first embodiment;

FIG. 3 is a front elevational view in accordance with the first embodiment;

FIG. 4 is a rear elevational view in accordance with the first embodiment;

FIG. 5 is a left elevational side view in accordance with the first embodiment;

FIG. 6 is a right elevational side view in accordance with the first embodiment;

FIG. 7 is a top plan view in accordance with the first embodiment;

FIG. 8 is a bottom plan view in accordance with the first embodiment;

FIG. 9 is a front perspective view of an access control machine in accordance with a second embodiment of the present design application;

FIG. 10 is a rear perspective view in accordance with the second embodiment;

FIG. 11 is a front elevational view in accordance with the second embodiment;

FIG. 12 is a rear elevational view in accordance with the second embodiment;

FIG. 13 is a left elevational side view in accordance with the second embodiment;

FIG. 14 is a right elevational side view in accordance with the second embodiment;

FIG. 15 is a top plan view in accordance with the second embodiment; and,

FIG. 16 is a bottom plan view in accordance with the second embodiment.

The broken lines in the figures depict portions of the access control machine that form no part of the claimed design.
